Solomon's Patent

It is the object of this new Solomons Patent, and a making part of the
Improvement, to describe in the name of the Solomons Patent Company
a new and useful Improvement in the construction of a door, window, or
other frame.

John Solomons, of Providence,
State of Rhode Island, has invented a new and useful Improvement
in the construction of doors, windows, &c., which may be thus described:

The invention consists in the following: The Slats are
joined by a rod in the center of them. The inner edge of each Slat is fast-
ened to this rod by a hinge, and in the middle of upper rail or Head
of the frame there is placed a slot in which the end of the rod is fastened
so that the Slats are closed. The Slats are freely moving, this will
allow them to open. This Improvement consists in suspending the rod
so as to be in connection with the Slats and substituting for its place what I call a
guide, on the inner or inner side of the Head. This guide is a thin
light-colored or hard wood a say one-eighth of an inch in thickness 7/8 of
an inch wide enough to leave sufficient space around it to
allow the Slats to attach to one end of every slot between each.
It is fastened to the Head by a pin or pivot of wood or metal, that passes into
the slot near the inner edge of the Slat, on this pin a pivot
is fastened as the Slats are opened or closed. The guide is between the two
Slats to which it is attached and the hinge or monogram in which they
are fastened so that it is shaped that it will not interfere with the
opening of the Slats and the Slats attached to each guide are turned by the
guide up and down by turning any one of the Slats. When the
Slats are fastened closed by inserting a pin or other fastening in the
slot, the hinge or monogram from the middle of the Head to the
center of the rod is fastened to the Head so turned by any position in the
frame, so that the hinge or monogram may be fastened to the Head in any
position in the frame. The hinge or monogram may be fastened to the Head in any
position in the frame.
